(No Model.)

E. M. BENTLEY.
ELECTRIC RAILWAY PLOW.

No. 400,180.

Patented Mar. 26, 1889.

UNITED STATES PATENT OFFICE

EDWARD M. BENTLEY, OF NEW YORK, N. Y.

ELECTRIC-RAILWAY PLOW.

SPECIFICATION forming part of Letters Patent No. 400,180, dated March 26, 1889.

Application filed December 5, 1888. Serial No. 292,697. (No model.)

To all whom it may concern:

Be it known that I, EDWARD M. BENTLEY, a citizen of the United States, residing at New York, in the county of New York, State of 5 New York, have invented certain new and useful Improvements in Electric-Railway Plows, of which the following is a specification.

My invention relates to electric railways in 10 which the contact device is free to change its position relative to the vehicle; and its object is to provide suitable connections between the contact device and vehicle which will be readily extended and contracted, according to 15 the movement of the contact device.

My invention therefore consists in certain novel extensible connections between the contact device and the car, as hereinafter described and claimed.

20 This invention I find of particular importance in a conduit system, where the plow is allowed a transverse movement relative to the vehicle, for the electrical connection must in this system be such as to permit the travel of 25 the plow from one extremity of its movement to the other, and the flexible conductor heretofore employed would be slack while the plow is moving back and forth, and would be liable to interfere with the moving parts or 30 to drag on the ground and become detached. The extensible connection, however, is an important factor in many other combinations, so that I do not intend to be confined to the specific way in which it is employed in this

35 application. Many different kinds of extensible connections also may be used besides the one herein shown, which consists of a link made of telescoping sections of conducting material, and is not easily broken or worn 40 out. When two links are employed, as in the drawings, they will brace the plow to some extent.

The accompanying sheet of drawings illustrates my invention, wherein—

45 Figure 1 is a front view of the plow, its guide, and the extensible connection, the conduit and conductors being shown in transverse section. Fig. 2 is an end view of the same. Fig. 3 is a detail view showing the link 50 in longitudinal section, and Fig. 4 is a modification of the extensible connection.

A represents a car-beam or other suitable support, forming part of an electrically-propelled vehicle designed to travel over the railway.

55

C is a contact device or plow movable relatively to the car.

D is a transverse guide, along which slides freely the supporting-head E of the plow.

The contact device or plow is capable of 60 being shifted from point to point upon the vehicle as the requirements of the service demand, and while the sliding movement which the contact device has upon the vehicle through guide D and traveler E is one way, 65 of thus shifting the contact device it could be done in many other different ways as well.

F is a conduit which may be placed outside of or between the rails, and in which two supply-conductors are inclosed.

70

B B are the two extensible connections, attached at their ends to the plow and car, respectively, and consisting of telescoping sections of metal, as many in number as may be desired. These links are connected to the 75 contact-shoes through a couple of contact-conductors embedded in an insulating-panel, and form the electrical connections leading to the vehicle. They also serve to brace the plow, and their upper ends are joined to the 80 car by universal joints, permitting freedom of movement in all directions.

A spring, H, may be employed in connection with the extensible links, as shown in Fig. 4.

85

I claim as my invention—

1. The combination of a vehicle and a contact device for engagement with a supply-conductor, with an intermediate mechanical connection permitting movement of the contact device relative to the vehicle, and an extensible electrical connection between the contact device and vehicle.

2. The combination of a vehicle and a guide thereon with the contact device movable 95 along said guide, and an extensible connection between the contact device and the vehicle.

3. The combination of the vehicle with a contact device capable of being shifted from point to point upon the vehicle, and an extensible connection between the contact device and the vehicle.

4. The combination of the vehicle and a transverse guide thereon with a contact device movable along said guide, and an extensible electrical connection between the contact device and vehicle. 55
5. The combination, in an electric railway, of two line-conductors and a collector having contact-surfaces engaging with said conductors with extensible connections in circuit 60 with said contact-surfaces and leading to the vehicle.
6. The combination of a vehicle with a contact device having a sliding movement thereupon and a connecting-link between the contact device and the vehicle, consisting of two or more sections extensible to one another. 65
7. The combination of a vehicle with a contact device capable of being shifted from point to point upon the vehicle, and a connecting-link between the contact device and the vehicle, consisting of a plurality of sections of conducting material extensibly connected together. 70
8. The combination of the conduit, the inclosed conductor, the vehicle, and transverse guide thereon, with the contact device movable along said guide, and an extensible connection between the contact device and the vehicle. 75
9. The combination of the conduit, the inclosed supply-conductors, the vehicle, and transverse guide thereon, with the plow movable along said guide, the contact-conductors carried by said plow, and the extensible electrical connections leading therefrom to the vehicle. 80
10. The combination of the conduit and inclosed supply-conductor with a contact device movable relatively to the vehicle, and an intermediate extensible connection one end of which is connected to the contact device and the other to the car. 85
11. The combination of the vehicle, a conduit, an inclosed conductor, and a contact device therefor, with a mechanical connection permitting movement of the contact device relatively to the vehicle and an extensible electrical connection between the contact device and the vehicle. 90
12. The combination of the vehicle, a conduit, and inclosed conductor, with a plow or current collector movable laterally relative to the vehicle and an extensible connection between the plow and vehicle. 95
13. The combination of the conduit, the inclosed conductor, the vehicle, and contact device capable of being shifted from point to point upon the vehicle, with an extensible connection between the contact device and vehicle. 60
14. The combination of a conduit, a conductor therein, and a contact device with an electrical connection between the contact device and car, consisting of telescoping sections of conducting material. 65
15. The combination of the conduit and inclosed conductor with a vehicle, a contact device connected thereto, and an extensible link between the contact device and the vehicle. 70
16. The combination of a vehicle and a plow having a movable connection therewith with extensible links leading from each side of the plow to the vehicle and bracing the plow. 75
17. The combination, in an electric railway, of the vehicle, the conduit, and inclosed conductor, with the contact device therefor and a connecting-link between the contact device and vehicle connected to one of them by a universal joint, thereby permitting freedom of movement. 80
18. The combination, in an electric railway, of a vehicle and a contact device connected thereto, with a conduit, an inclosed conductor, and an electrical connection between the contact device and vehicle, consisting of an extensible link of conducting material and a universal-joint attachment for the same. 85
19. The combination of the conduit and inclosed conductor with the transversely-moving contact device for the same, and an extensible spring-connection leading to the vehicle. 90
20. The combination of the conduit and inclosed conductor with the plow, a mechanical connection permitting transverse movement of the plow, and an extensible spring electrical connection between the plow and vehicle. 95

EDWARD M. BENTLEY.
